UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

Application filed April 23, 1924. Serial No. 709,475.

To all whom it may concern:

Be it known that I, GEORGE CLAUSING, a citizen of the United States, residing at Portsmouth, in the county of Scioto and State of Ohio, have invented certain new and useful Improvements in Lasts, of which the following is a specification, reference being had therein to the accompanying drawing.

10 My invention relates to lasts, and in particular to collapsible lasts.

It is the object of my invention to provide a collapsible last in which the halves of the last rock upon one another about a 15 common center.

It is a further object to provide yielding means to resist this movement from one position to the other. It is a further object to provide a connecting means the points of 20 connection of which on each last half will be below the pivotal center of the last halves when the last is expanded and above said center when the last is collapsed.

It is a further object of my invention to 25 provide an articulated connecting link between the last halves which will permit of the movement of said last halves about one another although the points of connection of the link parts to the respective last halves 30 are fixed and the distance between said points of connection will tend to vary as the parts are moved from one position to the other. It is a further object to provide yielding means to resist the movement of 35 articulation of the connecting link.

Referring to the drawings:

Figure 1 is a section through the last revealing the connecting mechanism with the last in expanded position.

40 Figure 2 is a similar view with the last in collapsible position.

Figure 3 is a plan view of the details of the connecting mechanism.

Referring to the drawings in detail:

45 1 is a toe part of the last which has a cut-away portion 2 for receiving a portion of the connecting mechanism.

The front half of the last is provided with a vertical rear face or substantially vertical 50 face 3, the lower portion of which is cut away in a semicircular concavity 4. This rear face terminates in the substantially vertical lower portion 5 which corresponds to a similar portion 6 on the front of the lower 55 part of the rear or heel portion of the last,

7. This front face of the heel part of the last is provided with a semicircular projection or shoulder 8 which describes an arc something greater than 180 degrees. The upper part of the front face of the heel part 60 of the last is extended upwardly and rearwardly as at 9 so that the space between the faces 3 and 9 permits the last halves to collapse while the faces 5 and 6 limit their movement in their expanded position. The 65 knuckle joint composed of the shoulder 8 and concave depression 4 provides a suitable ball and socket type of joint for the pivoting of the last parts substantially about the center 10. The rear half of this last is also 70 cut away as at 11 to receive some of the connecting parts. The front part of the last is provided with a transverse pin 12 and the rear or heel part of the last provided with 75 a transverse pin 13.

A semicircular link segment 14 is pivoted near one end on the pin 12. It is pivotally connected at its other end on the pin 15 to the ends of connecting plates 16 and 17. The free end of this link segment is composed of an upper, substantially vertical portion 18 and a cutaway portion 18^a, so that this end can rock upon a similarly formed end of a companion, oppositely disposed, link segment 19, which is connected 80 at 20 to the other ends of the connecting plates 16 and 17. The segmental link 19 is pivotally mounted on the pin 13. The lower ends of the links 14 and 19 are provided with downwardly extending, oppositely disposed hooks. The hook on the link 14 is designated 21 and the hook on the link 19 is designated 22. Mounted on these hooks and connecting them is a coil spring 23 which serves to resist the rocking of the 85 link segments on the pins 12 and 13.

It will be observed that this connection of the spring with the link segments is always below the pivotal center 10 and is below the points of connection or mounting of the link segments on the respective pins 12 and 13. It will be noted that the last, which is preferably made of wood, is somewhat compressible, which is a matter of advantage due to the fact that the distance between the centers 100 of the pins 12 and 13 will increase and decrease as the parts are moved from collapsed to expanded position or vice versa. The spring 23 will resist this movement because the link segments will rock on the pins 12 105 110

and 13 and the ends of these link segments will rock upon one another during this movement from one position to the other of the last halves.

5 It will be understood that I desire to comprehend within my invention such modifications as may be necessary to adapt my invention to varying conditions of use.

Having thus fully described my invention, what I claim as new and desire to secure by Letters Patent, is:

1. In a last, a toe part and a heel part adapted to rock about on one another, segmental links mounted in either part, adapted to have their free ends rock on one another, and yielding means connecting their other ends, whereby when the last parts are moved from one position to another, such movement will be yieldingly resisted and 20 said segments will rock on one another.

2. In a last, a heel part and a toe part adapted to rock upon one another, an articulated link connecting said parts, means to pivotally mount the ends of said link on 25 the respective parts and yielding means connected with said link to resist the movement of the parts from one position to the other.

3. In a last, a heel part and a toe part adapted to rock upon one another, an articulated link connecting said parts, means to pivotally mount the ends of said link on the respective parts and yielding means connected with said link to resist the movement of the parts from one position to the other, 35 the points of connection of the link to the last parts being below the point about which the parts pivot when the last is expanded and above such point when the last is collapsed.

40 4. In a last, a heel part and a toe part, a shoulder on one part having a semicircular surface fitting into a semicircular depression on the other part and said last parts being cut away so as to permit their collapsing and so as to limit their expansion, and an articulated link connecting said parts arranged for the parts of the link to rock upon one another as the parts of the last pass from one position to the other.

45 5. In a last, a heel part and a toe part, a shoulder on one part having a semicircular surface fitting into a semicircular depression on the other part and said last parts being cut away so as to permit their collapsing and so as to limit their expansion, an articulated link connecting said parts arranged for the parts of the link to rock upon one another as the parts of the last pass from one position to the other, and 60 yielding means connected to the free ends of said link to resist this movement of the last parts.

6. In a last, a heel part and a toe part, a shoulder on one part having a semicircular surface fitting into a semicircular depression

on the other part and said last parts being cut away so as to permit their collapsing and so as to limit their expansion, an articulated link connecting said parts arranged for the parts of the link to rock upon one another as the parts of the last pass from one position to the other, and yielding means connected to the free ends of said link to resist this movement of the last parts, the points of connection of the link on the last parts and the yielding means being located below such points of connection.

7. In a last, last halves comprising a toe part and a heel part adapted to rock upon one another about a common center, an 80 articulated link joining said last halves, said link being mounted on transverse pins mounted in the respective halves of said last, and a spring connected to hooks carried on the free ends of said link below the points of connection of the link to the last halves, said points of connection being arranged so that a line drawn therebetween will pass over the pivotal center about which the last halves move when the last halves are moved from one position to the other, the distance between said centers of connection varying as the movement takes place.

8. In a last, last halves comprising a toe part and a heel part adapted to rock upon one another about a common center, an articulated link joining said last halves, said link being mounted on transverse pins mounted in the respective halves of said last, and a spring connected to hooks carried on the free ends of said link below the points of connection of the link to the last halves, said points of connection being arranged so that a line drawn therebetween will pass over the pivotal center about which the last halves move when the last halves are moved from one position to the other, the distance between said centers of connection varying as the movement takes place, 95 said last halves being composed of compressible material to accommodate the passing of the last halves so connected from one position to the other.

9. In a last, a heel part, a toe part, a transverse pin located in either part of the last, said parts being arranged to rock on one another about a common center, a segmental link mounted on the respective pins having abutting ends partially cut away to permit said ends to rock on one another, connecting plates connecting said ends and pivotally mounted on such ends of the link segments and downwardly extending connecting means on the lower ends of said link segments below their points of connection on the last and yielding means mounted thereon connecting the lower ends of said link segments whereby as said last parts move from one position to the other said spring will be flexed and the link segments will rock upon 120 125 130

one another accommodating the movement of the last parts and yieldingly resisting it.

10. In a last, a heel part, a toe part, a transverse pin located in either part of the last, said parts being arranged to rock on one another about a common center, a segmental link mounted on the respective pins having abutting ends partially cut away to permit said ends to rock on one another, 5 connecting plates connecting said ends and pivotally mounted on such ends of the link segments and downwardly extending connecting means on the lower ends of said link segments below their points of connection on the last and yielding means mounted thereon connecting the lower ends of said link segments whereby as said last parts move from one position to the other said spring will be flexed and the link segments will rock upon one another accommodating the movement of the last parts and yieldingly resisting it, said last parts being composed 10 of compressible material to accommodate the extension of the distance between the points of connection of the segments to the last parts, said points of connection being so arranged that a line drawn between their centers will pass over the center about which the last parts are pivoted as said last parts move from one position to the other.
- 15 the last and yielding means mounted thereon connecting the lower ends of said link segments whereby as said last parts move from one position to the other said spring will be flexed and the link segments will rock upon 20 one another accommodating the movement of the last parts and yieldingly resisting it, said last parts being composed of compressible material to accommodate the extension of the distance between the points of connection of the segments to the last parts.
- 25

11. In a last, a heel part, a toe part, a transverse pin located in either part of the last, said parts being arranged to rock on one another about a common center, a segmental link mounted on the respective pins having abutting ends partially cut away to 30

permit said ends to rock on one another, connecting plates connecting said ends and pivotally mounted on such ends of the link segments and downwardly extending connecting means on the lower ends of said link segments below their points of connection on the last and yielding means mounted thereon connecting the lower ends of said link segments whereby as said last parts move from one position to the other said spring will be flexed and the link segments will rock upon one another accommodating the movement of the last parts and yieldingly resisting it, said last parts being composed 35 of compressible material to accommodate the extension of the distance between the points of connection of the segments to the last parts, said points of connection being so arranged that a line drawn between their centers will pass over the center about which the last parts are pivoted as said last parts move from one position to the other.

12. In a last, a toe part and a heel part adapted to rock about on one another, and segmental links mounted in either part and adapted to have their free ends abut and rock on one another.

In testimony whereof, I affix my signature.

GEORGE CLAUSING.
